LADDER

Robert W. Hull, Connersville, Ind., assignor to
Rex Manufacturing Company, Connersville,
Ind., a corporation of Indiana

Application August 26, 1935, Serial No. 37,970

8 Claims. (Cl. 228—59)

This invention relates to a ladder of metal having wood inserts or reinforcements.

Heretofore ladders have been constructed of various materials, in various ways and used for various purposes. However, these ladders have lacked certain desirable features and have been found to be of clumsy and bulky construction, expensive, subject to breakage easily and therefore unsafe, susceptible to deterioration on account of weather conditions, moisture, insects and other causes.

It is an object of the invention to provide a new improved ladder of more durable, flexible, reliable and less expensive yet safer and stronger construction and capable of resisting the inroads of time, weather and insects.

A further object of the invention is to provide an improved process of forming and fabricating a ladder.

20 Other objects and advantages of the invention will be apparent from the following description taken in connection with the accompanying drawing wherein,

Fig. 1 is a front elevation of a ladder constructed in accordance with the present invention;

Fig. 2, a side elevation of the same except that the wooden strips are of sectional construction;

Fig. 3, an exploded view showing one side of 30 the ladder in cross-section and a rung located therein;

Fig. 4, a fragmentary inside view of one of the side members showing in section a rung secured in place;

Fig. 5, a detail illustrating the manner in which the rung is fastened in the side member; and,

Fig. 6 is a transverse section through one of the side members of the ladder.

Referring to the drawing, the ladder shown 40 comprises wooden side members or fillers 10 which are provided with metal casings or covers 11. The extremities of the filler members 10 project beyond the extremities of the metal covers or sheaths and are rounded as shown in order that 45 the lower end of the ladder will rest solidly upon a support and the upper end of the ladder will solidly engage a wall or the like against which the ladder rests when in position. The side members are connected by means of rungs formed of 50 wooden inserts 12 and metal casings 13 therefor.

The metal sheaths or covers for the side members of the ladder as best shown in Fig. 6, are provided with internal ribs 14 for strengthening and for securing better engagement between the 55 covers 11 and the wooden inserts 10. The inner

edges 15 of each metal sheath are crimped into the wooden filler 10 to form a tight seal therewith and sufficiently to be countersunk and have their outer surfaces flush with the exposed surface of the wooden filler.

5 The rungs of the ladder are of a diameter corresponding to the distance of the spacing of the edges 15 in order that the rungs may be seated or securely anchored or fastened therein, the wood filler members 10 being provided with a 10 socket or receiving opening 16 of a diameter substantially corresponding to the external diameter of the rung. The end of each rung is secured in the socket in the side member by a key or wedge member 17 which deforms the metal casing for 15 the rung outwardly, providing bulges 11', into the wooden insert as shown in Figs. 4 and 5. Each wooden insert 12 is provided with a longitudinal peripheral groove 18 to receive the end of the turned edges 19 of the metal which forms the 20 metal casing 13.

It will be readily understood from the preceding description that the ladder just described consists of metal side casings, each of which is mounted upon or encloses a wooden filler member 25 of a unitary or sectional or spliced construction with its ends projecting from the top and bottom of the ladder or not as desired to form a vertical support for the base of the ladder and a lateral support for the upper end of the ladder.

30 The ladder can be constructed in a number of different ways by hand or by machinery but in actual experience, I have found that the more tightly united the wood and metal members are, the more improved is the finished article and 35 consequently reduced cross-sectional dimensions can be employed.

Where lumber is difficult to obtain in considerable lengths, short sections can readily be employed, the joint between the sections being preferably tapered as shown in Fig. 2 to cause a 40 wedging of the several sections.

In assembling the ladder, rungs are applied one at a time in one section or a group of rungs are placed simultaneously in such side sections and 45 an opposed side section is placed in position and the two side sections are forced each toward the other. It will be readily appreciated of course that before the side sections have the rungs applied that such side sections must be provided 50 with rung receiving sockets 16 and wedges 17 placed in position in such sockets so that the wedging action shown in Fig. 5, will be accomplished when the sides of the ladder are pressed together.

It will be readily apparent that a ladder of the above described construction is not only of less weight than ordinary ladders in use at the present time but also of less bulky construction, 5 of many times greater strength, durability, flexibility and free from the many objectionable features ordinarily encountered.

- The ladder may be treated to prevent wood insects from attacking the wood and the metal may 10 be of the corrosion resistant type. With a ladder of this construction when the upper extremity is placed against an offset, the ladder will yieldingly twist to accommodate itself to its lateral support. 15 It will be obvious to those skilled in the art that various changes may be made in my device without departing from the spirit of the invention and therefore I do not limit myself to what is shown in the drawing and described in the 20 specification but only as indicated in the appended claims.

I claim:

1. A ladder comprising longitudinally ribbed metal side casings and metal rungs provided with 25 wooden filler pieces, said metal side casings being clamped about the wooden filler pieces into tight contact therewith, and in such relation thereto that at least one filler piece projects from at least one metal side casing.
2. A ladder comprising side members, each formed of a longitudinally ribbed metal casing and a wooden insert, and rungs connecting said side members, said rungs being formed of metal casings with wooden inserts, said rungs having 30 their extremities anchored in said side members, and a wedge at the end of each rung within the casings of the side members deforming the ends of the rung casing for maintaining the rung in anchored position in said side member.
3. A ladder comprising side members, each having a metal casing and a wooden filler member, said metal casing being pressed into intimate contact with said filler member and having 35 its edges disposed in spaced relation, said filler member having rung sockets of a diameter cor-

responding to the distance between spaced edges of the casing.

4. A ladder comprising side members, each having a metal casing and a wooden filler member, said metal casing being pressed into intimate contact with said filler member and having its edges disposed in spaced relation, said filler member having rung sockets of a diameter corresponding to the distance between spaced edges of the casing, a wedge in the bottom of said socket 10 and having its extremities tapered and forming a metal casing for the rung located in said socket for anchoring the rung in the side member.

5. A ladder comprising side members, each formed of a metal casing with an insert, said 15 metal casing being provided with longitudinal reinforcing ribs and said insert being configured to conform to the ribbed portion of the casing, the edges of the metal casing being pressed into intimate relation with the said filler, and in such 20 relation thereto that at least one end of said insert projects from said casing.

6. A ladder comprising side members, each formed of a metal casing with an insert, said 25 metal casing being provided with longitudinal reinforcing ribs and said insert being configured to conform to the ribbed portion of the casing, the edges of the metal casing being pressed into intimate relation with the said filler with the remote ends of the filler projecting beyond the ends 30 of the casing.

7. A ladder comprising metal encased side members and metal encased rungs connecting said side members, and wedges enclosed within the side member casings and engaging in the extremities of said rungs anchoring the rungs to 35 the side members.

8. A relatively strong flexible ladder comprising metal encased side members and metal encased rungs, the casing for each rung being 40 formed of a substantially cylindrical sleeve with an inner seam formed by the abutting edge portions of the metal, said rung having a longitudinal groove receiving said seam.
